(57) **CLAIM**

The ornamental design for a door release trim, as shown and described.

DESCRIPTION

FIG. 1 is an isometric view of a door release trim, showing an embodiment of our new design.

FIG. 2 is another isometric view thereof.

FIG. 3 is a front elevational view thereof.

FIG. 4 is a rear elevational view thereof.

FIG. 5 is a left side elevational view thereof.

FIG. 6 is a right side elevational view thereof.

FIG. 7 is a top plan view thereof.

FIG. 8 is an isometric view of a door release trim, showing another embodiment of our new design, which is a mirror image of the door release trim shown in FIGS. 1-7.

FIG. 9 is another isometric view thereof.

FIG. 10 is a front elevational view thereof.

FIG. 11 is a rear elevational view thereof.

FIG. 12 is a left side elevational view thereof.

FIG. 13 is a right side elevational view thereof; and,

FIG. 14 is a top plan view thereof.

Stippling in the drawings represent the three-dimensional contours of the design, and is not intended to indicate surface decoration. The broken lines shown in the drawings depict portions of the door release trim that form no part of the claimed design.
